(57) **ABSTRACT**

A vibration therapy device that includes a housing that includes a handle portion, a head portion, and a module seat defined on the head portion, an electrical source, a motor positioned in the housing, a switch for activating the motor, a push rod assembly operatively connected to the motor, a reciprocating attachment removably secured to a distal end of the push rod assembly and configured to provide a first type of therapy, and a therapy module removably secured to the module seat and configured to provide a second type of therapy.

VIBRATION THERAPY SYSTEM AND DEVICE

CROSS-REFERENCE TO RELATED APPLICATIONS

This application is a continuation of U.S. patent application Ser. No. 17/568,330, filed Jan. 4, 2022, which is a continuation-in-part of U.S. patent application Ser. No. 17/361,966, filed Jun. 29, 2021, now U.S. Pat. No. 11,331,244, which claims the benefit of U.S. Provisional Application No. 63/133,530, filed Jan. 4, 2021, U.S. Provisional Application No. 63/065,348, filed Aug. 13, 2020, and U.S. Provisional Patent Application No. 63/045,365, filed Jun. 29, 2020, the entireties of which are incorporated by reference herein.

FIELD OF THE INVENTION

The present invention relates generally to a vibration therapy system and device, and more particularly to a cooling attachment module that can be used with the vibration therapy device.

BACKGROUND OF THE INVENTION

As people age, devices for skin and facial care are needed. Percussive massage devices that provide reciprocating motion and provide relief to sore muscles and other parts of the body are known. For example, see U.S. Pat. Nos. 10,857,064 and 10,945,915, the entireties of which are incorporated by reference herein. However, many percussive massage devices may be uncomfortable if used on the face and principally target the underlying muscles. The present invention addresses the needs discussed herein.

The background description disclosed anywhere in this patent application includes information that may be useful in understanding the present invention. It is not an admission that any of the information provided herein is prior art or relevant to the presently claimed invention, or that any publication specifically or implicitly referenced is prior art.

SUMMARY OF THE PREFERRED EMBODIMENTS

In accordance with a first aspect of the present invention there is provided a cooling attachment module for use with a vibration therapy device that includes a housing and/or heat sink member that includes inner and outer walls and defines a central opening axially therethrough. A cooling recess is defined in an upper surface and a connection recess is defined in a lower surface of the heat sink member. A cover member is secured over the cooling recess. A controllable temperature element is positioned on an upper surface of the heat sink member. A spreader member is positioned on an upper surface of the controllable temperature element. An upper surface of the spreader member is positioned above an upper surface of the cover member to contact a user's body part. The controllable temperature element is configured to transfer thermal energy to a lower surface of the spreader member. A base portion that includes an electrical connector is secured under the electrical recess. In a preferred embodiment, the cover member includes at least a first cooling protrusion opening defined therein, the spreader member includes at least a first cooling protrusion extending

upwardly therefrom, and the cooling protrusion extends through the cooling protrusion opening and above the upper surface of the cover member.

In a preferred embodiment, the base portion includes a plurality of magnets therearound. Preferably, an electrical control member is associated with the base portion. The electrical connector comprises a plurality of male electrical contacts extending downwardly from the electrical control member and into a securement recess defined in a lower surface of the base portion. Preferably, the heat sink member includes at least a first electrical communication tunnel defined therethrough and power is routed from the electrical connector through the first electrical communication tunnel and to the controllable temperature element. In a preferred embodiment, the heat sink member is made of metal and the cover member and base portion are made of a non-metal (e.g., plastic). Preferably, the heat sink member is much thicker than the controllable temperature element, which allows the heat sink member to act as a heat sink and dissipate heat. The heat sink member (or at least the inner and outer walls thereof) may be between 2 to 10 times thicker (in an axial direction) than the controllable temperature element.

In accordance with another aspect of the present invention 25 there is provided a cooling attachment module for use with a facial treatment device that includes a heat sink member having inner and outer walls and defines a central opening axially therethrough. A cooling recess is defined in an upper surface and a connection recess is defined in a lower surface. 30 The heat sink member includes one or more electrical communication tunnels defined therethrough and the heat sink member is made of metal. A cover member is secured over the cooling recess. The cover member includes first and second arcuate shaped cooling protrusion openings defined 35 therein and the cover member is made of non-metal. First and second controllable temperature elements are positioned on an upper surface of the heat sink member. A spreader member is positioned on an upper surface of the first and second controllable temperature elements. The spreader member includes first and second arcuate shaped cooling protrusions extending upwardly therefrom that extend through the cooling protrusion opening and above the upper surface of the cover member to contact a user's body part. 40 The first and second controllable temperature elements are configured to transfer thermal energy to a lower surface of the spreader member. A base portion is secured under the electrical recess. The base portion includes a plurality of magnets therearound and is made of non-metal, and an electrical control member is positioned in the electrical recess. 45 The electrical connector comprises a plurality of male electrical contacts extending downwardly from the electrical control member and into a securement recess defined in a lower surface of the base portion. Power is routed from the male electrical contacts through the electrical communication tunnel(s) and to the first and second controllable temperature elements. Preferably, first and second isolation washers are positioned in a component tunnel defined between the upper surface and the lower surface of the heat sink member.

In accordance with another aspect of the present invention 50 there is provided a vibration therapy device that includes the cooling attachment module removably secured to the module seat. The cooling attachment module at least partially surrounds the distal end of the push rod assembly.

In accordance with another aspect of the present invention 55 there is provided a vibration therapy device that includes a housing that includes a handle portion, a head portion and a

module seat defined on the head portion, an electrical source, a motor positioned in the housing, a switch for activating the motor, a push rod assembly operatively connected to the motor and configured to reciprocate in response to activation of the motor, and a therapy module removably secured to the module seat. The distal end of the push rod assembly is configured to removably receive a reciprocating attachment thereon. The therapy module at least partially surrounds the distal end of the push rod assembly. In a preferred embodiment, the push rod assembly includes an attachment member that defines the distal end of the push rod assembly. The therapy module is coaxial with the distal end of the push rod assembly (e.g., the attachment member and/or the magnet seat), and at least a portion of the attachment member (e.g., the magnet member) extends into the therapy module.

In a preferred embodiment, the therapy module is in electrical communication with the electrical source (so that it can be powered) and/or is in data communication with the controller/processor of the device (so that it can be operated as desired). For electrical connection, the module seat preferably includes a first electrical connector (male or female), and wherein the therapy module includes a second electrical connector (female or male) in electrical communication with the first electrical connector. The therapy module may comprise a ring module that includes a central opening and an outer surface. When a reciprocating attachment that includes a contact surface is removably received on the distal end of the push rod assembly, the contact surface of the reciprocating attachment extends further from the module seat than the outer surface of the ring module.

The therapy module may be a ring module that includes a plurality of LED's therein or thereon. The LEDs are configured to operate at a treatment level only when the outer surface is less than a predetermined distance from an operating surface. In a preferred embodiment, the ring module further includes at least first and second proximity sensors that are positioned approximately 180° from one another within the ring module (e.g., on the PCB). The first and second proximity sensors are each configured to activate the LEDs at the treatment level when the outer surface of the ring module is less than the predetermined distance from the operating surface.

The therapy module may comprise a cap module that includes a main body portion with a closed distal end and a rear recess and where at least a portion of the attachment member extends into the rear recess. The cap module may include an anode and a cathode and may be configured to provide micro-current therapy. The cap module may also be configured to be removably secured to the module seat and the attachment member. In this embodiment, the cap module may be removably secured to the module seat via magnets and/or one or more securement protrusions and recesses (that also help properly align the cap module).

In accordance with another aspect of the invention there is provided a vibration therapy system that includes a vibration therapy device, a ring module that includes a central opening and that is configured to be removably secured to the module seat, a cap module that includes a main body portion and a rear recess and that is configured to be removably secured to the module seat, and a reciprocating attachment that is configured to be removably received on the attachment member. When the ring module is removably secured to the module seat, the distal end of the push rod assembly extends into the central opening. When the cap module is removably secured to the module seat, the distal end of the push rod assembly extends into the rear recess.

When the ring module is received on the module seat, the reciprocating attachment extends through the central opening. When the ring module is received on the module seat the attachment member can be reciprocated, and when the cap module is received on the module seat the attachment member cannot be reciprocated.

In accordance with another aspect of the invention there is provided a vibration therapy device that includes a housing that includes a handle portion and a head portion an 10 electrical source, a motor positioned in the housing, a switch for activating the motor, a push rod assembly operatively connected to the motor and configured to reciprocate in response to activation of the motor, and a reciprocating attachment removably secured to a distal end of the push rod assembly. The reciprocating attachment includes a contact 15 surface, and a skin treatment member is removably secured to the reciprocating attachment such that a delivery portion at least partially covers the contact surface. In a preferred embodiment, the reciprocating attachment includes a groove defined therein and at least a portion of the skin treatment member is received in the groove. Preferably, the skin treatment member includes a main body portion that, together with the delivery portion, defines an attachment recess. At least one ridge member extends inwardly from the 20 main body portion into the attachment recess and is received in the groove on the reciprocating attachment. In a preferred embodiment, the delivery portion includes a lotion or other formulation thereon.

Described herein is a vibration therapy device that 30 includes interchangeable attachments that provide therapy to a user. The interchangeable attachments can include, for example, LED light therapy, micro-current, etc. Generally, the present invention is a vibration therapy device that includes LED lights thereon that can be used for skin therapy. LED skin therapy is known. For example, see U.S. Pat. Nos. 6,524,329 and 6,974,224, the entireties of which are incorporated by reference herein.

The present invention is a hand-held vibration facial massager or vibration therapy device that includes different 40 therapy attachments compatible therewith. The hand-held device, which is intended to be used on the face, but can also be used anywhere else on the body, combines vibration therapy with other facial treatment technologies, including, but not limited to, LED light therapy, micro-current treatments and radio frequency skin technology.

As discussed below, the vibration therapy treatment can be delivered by a brushless motor-drive train system with the distal end of the reciprocating output shaft including an amplitude of preferably between 2.0 mm and 8.0 mm. It will 50 be appreciated that this small amplitude of reciprocation is referred to herein as a vibrating movement or vibration, hence the phrase "vibration therapy device." However, the amplitude can be anywhere between 1.0 mm and 25 mm. The removable or interchangeable vibration therapy attachment on the end of the output shaft can be any type of attachment (see, e.g., the patents discussed above). In a preferred embodiment, the attachment is a foam/rubber attachment that is connected to the end of the shaft to deliver the vibration to the user's face. See, e.g., U.S. Pat. No. 60,10,758,452, the entirety of which is incorporated by reference herein.

The present invention includes an attachment system to accommodate swappable or interchangeable rings or modules with different facial treatment technologies. For example, the module can be a blue, red, amber and/or infrared LED light therapy light ring module or can be a module that includes micro-current therapy, RF (radio fre-

quency) therapy, heat, cold, electric stimulation and/or vibration (e.g., the therapy module can include one or more motors or the like that provide vibration, separate from the reciprocation of the reciprocating attachment). As discussed below, in a preferred embodiment, the device includes an electrical connection system to deliver electric power to the ring or module and a magnet-based system to secure the ring or module in place.

In one preferred embodiment, the magnets are programmed or polymagnets. Polymagnets are magnetic structures that incorporate correlated patterns of magnets with alternating polarity, designed to achieve a desired behavior and deliver stronger local force. By varying the magnetic fields and strengths, different mechanical behaviors can be controlled. Correlated magnet pairs can be programmed to attract or repel with a prescribed force and engagement distance, or, to attract or repel at a certain spatial orientation. Correlated magnets can be programmed to interact only with other magnetic structures that have been coded to respond. As a result, a strong force can be used to hold the module on the device, but a fairly weak force can be used for removing the module. For example, the user can rotate the module about the module's central axis to a predetermined point where the module can be easily removed. The polymagnets in the device can even repel the polymagnets in the module at a certain rotation point, thus making removal of the module very easy. The polymagnets change properties based on the distance and position of the magnets in the ring module and the device with respect to one another. This allows the locking and unlocking forces that the user needs to apply to connect and disconnect the module from the device to be reduced compared to the use of regular magnets. For example: the magnets can repel each other when the distance between them is more than one inch but if they are brought closer than one inch they attract each other. Therefore, for example, at a first distance and a first degree of rotation, the force required to secure the module or push the module into place on the module seat (referred to herein as "attach the module") is X and at the first distance and a second degree of rotation, the force required to attach the module is Y, where Y is less than X. To detach the module or pull it off the device, the force required may be A at a first set of degrees of rotation and B at a second set of degrees of rotation, where A is less than B. For example, the first set of degrees of rotation may be 0° to 15° and the second set of degrees of rotation may be 16° to 360°. Therefore, when the module or attachment is rotated to an angle between 0° to 15° it is easy to remove. At any other angle it is difficult for the user to remove.

In a preferred embodiment, the device and/or system also includes a software application downloadable to a portable electronic device that includes the ability to control the treatment and build different protocols via Bluetooth and the like.

In a preferred embodiment, the device and/or the therapy module includes a proximity sensor that detects the distance between the device and the user's face so that the therapy or treatment can be modified accordingly. For example, the light ring module can include one or more proximity sensors so that the LED lights can be dimmed and/or turned off when the device is pulled away from the user's skin and is not within a predetermined distance (i.e., when the ring is far enough from the user's face that no treatment is being provided). This may be done to save battery, for eye safety purposes or for other skin safety issues or concerns.

In a preferred embodiment, the handle forms an angle of about 120 degrees with the attachment arm or output shaft

to avoid blocking the user's view during treatment. In a preferred embodiment, the housing includes a female charging jack for receiving a male connector and charging the battery. The device also includes one or more buttons or switches for controlling the device (e.g., on/off, speed control, change color of LEDs, etc.) and LEDs that provide indication of different functions, such as battery power or speed setting, etc.

In a preferred embodiment, the vibration therapy device 10 includes a motor, battery, housing, and push rod assembly with a reciprocating shaft. The reciprocating shaft includes a male or female attachment member on the end thereof to which a massage or vibration attachment (that includes a corresponding female or male attachment member thereon) 15 can be attached. In a preferred embodiment, the massage attachment is secured to the vibration therapy device using magnets. When the device is used with a ring module or attachment vibration attachment extends through the center of the ring. Any type of attaching or securing arrangement 20 between the massage attachment and the vibration therapy device is within the scope of the invention. In a preferred embodiment, the amplitude is between about 2 mm and about 8 mm, which is smaller than many percussive massage devices. However, in another embodiment, the amplitude 25 can be greater and between 1 mm and 26 mm or more.

In a preferred embodiment, the motor converts power from the power source into motion. In some embodiments, the motor is an electric motor. The electric motor may be any type of electric motor known in the art, including, but not limited to, a brushed motor, a brushless motor, a direct current (DC) motor, an alternating current (AC) motor, a mechanical-commutator motor, an electronic commutator motor, or an externally commutated motor. In a preferred embodiment, the motor is a brushless direct-current (BLDC) 30 motor. Preferably, the percussive massage device includes a voltage-sensing resistor electrically coupled to the BLDC motor and a controller.

In a preferred embodiment, the vibration therapy device 40 includes a removable light ring therapy module that surrounds the massage or reciprocating attachment. In a preferred embodiment, the light ring module includes a plurality of lights (e.g., LED's). Preferably, the light ring module is electrically connected to the vibration therapy device when it is attached thereto so that the battery powers the lights. The light ring module includes a central opening that 45 at least partially surrounds the reciprocating attachment.

In a preferred embodiment, a plurality of different ring modules are included either separately or sold as a kit with the vibration therapy device. For example, separate ring 50 modules can include lights with different wavelengths (e.g., red LEDs on one ring and blue LEDs on another). In another embodiment, lights with different wavelengths can be included on the same ring (e.g., blue and red LEDs on the same ring). The rings are interchangeable. The rings can be 55 different sizes. Each of the ring modules can provide different functions or features. Some of the features can be used in conjunction with the vibration therapy massage attachment and others can be used with a massage attachment attached to the device. For example, the ring modules can 60 include (either individually or in combination) heat, vibrations, electrodes for electrolysis and/or emitting electromagnetic pulses. As a result, the main device acts as a power source for powering all of the different ring modules and the therapy modules that cover the attachment member where 65 the reciprocating attachment is seated. Therefore, the connected ring module can be used in conjunction with the reciprocating attachment or without the reciprocating attach-

ment (e.g., with the attachment removed), so the outer surface of the ring module can be placed against the user's skin, if necessary for the type of treatment being administered.

In another embodiment, the LEDs and/or one or more of any of the other treatments or discussed herein (e.g., micro-current, temperature, cleansing, etc.) can be part of the vibration therapy device and not removable. In a preferred embodiment, the control center or user interface includes an up button, a down button and a select button, which can be used for scrolling or toggling through various modes, going up or down in intensity or mode and selecting the modes or modules or turning different functions (vibration, light, micro-current, etc.) on or off.

It will be appreciated that the vibration therapy device together with the therapy module and reciprocating attachment may be referred to herein as a vibration therapy system.

In a preferred embodiment, the light ring module (or other ring module) includes alignment or securement recesses defined in a rear side thereof that receive the securement protrusions. Magnet members are positioned in the ring and adjacent the securement recesses. It will be appreciated that the magnet members associated with the securement recesses are magnetically attracted to the securement protrusions.

In a preferred embodiment, the motor is preferably attached to a motor mount bracket that secures the motor to the housing. Preferably, the motor mount bracket includes a middle member having first and second opposite sides. The motor is positioned on the first side and the eccentric weight is positioned on the second side of the middle member. The push rod assembly comprises an L-shaped or curved connector or push rod (connected to the eccentric weight) and the reciprocating shaft (with pivotal connections therebetween). The middle member includes a shaft opening defined therein. The motor includes a rotatable motor shaft extending therefrom that extends from the first side of the middle member, through the shaft opening and to the second side of the middle member. In a preferred embodiment, the motor mount bracket includes a battery bracket portion extending therefrom that secures the battery in place.

Generally, when the therapy module is attached, the head portion of the vibration therapy device includes two concentric attachment rings, the inner one for the reciprocation or massage attachment (e.g., silicone vibration head) and the outer one for the therapy modules (e.g., LED, Micro-current etc.). In a preferred embodiment, the male attachment also includes magnets for attachment (or similar attachment mechanism) and can also include an electrical connection similar to the outer ring. Therefore, a single attachment that covers both the outer and inner part can be used that attaches to male attachment and securement protrusions, for example to accommodate more LEDs.

In another preferred embodiment, the reciprocating attachment can include hooks for securing a microfiber material on the reciprocating attachment that can be used on the user's face or other body part for the vibration therapy treatment. The microfiber material is secured on both sides and under the reciprocating attachment and stretches across the top contact surface of the reciprocating attachment. The microfiber material can include lotion therein for treating the persons' skin.

It will be appreciated that different types of massage or reciprocating attachments can be used on the vibration therapy device. As discussed herein, one or more of the reciprocating attachments can include a groove extending

therearound for attachment of a treatment member (for treating the user's skin). Another massage attachment can include a cone portion or be cone shaped. Another massage attachment can include a soft portion and a harder portion that are connected by velcro. Another massage attachment can include a plurality of spikes or needles that provide a microneedling type treatment.

In a preferred embodiment, the present invention includes a ring module for use with the vibration therapy device that includes temperature control or the ability to apply heat or cold to the user's skin. In a preferred embodiment, the temperature controllable ring module includes a fan, a heat sink, a controllable temperature element (e.g., peltier module or device), and a temperature conductive plate that are contained within (or are at least partially contained within) a module housing with a center opening in which the massage attachment reciprocates. Temperature control modules are discussed in U.S. patent application Ser. No. 17/554, 10 305, filed Dec. 17, 2021 and U.S. Pat. No. 10,406,024, the 15 20 entireties of which are incorporated herein by reference.

The fan and heat sink are used to dissipate heat from the controllable temperature element. In a preferred embodiment, the heat sink is shaped such that it is in direct contact with the housing of the ring module. The fins of the heat sink can be shaped so they extend away from the controllable temperature element and to (in contact with) the wall of the ring module housing. Therefore, the ring module uses the 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 FIG. 4 is a cross-sectional view of the vibration therapy device;

FIG. 5 is a cross-sectional view of a portion of the vibration therapy device taken along 5-5 of FIG. 4;

FIG. 6 is a cross-sectional view of a portion of the vibration therapy device showing the securement protrusions and securement recesses with the electrical connection and magnetic connection;

FIG. 7 is a rear perspective view of the light ring module;

FIG. 8 is an exploded perspective view of the light ring module;

FIG. 9 is a perspective view of the vibration therapy device with the micro-current cap module thereon;

FIG. 10 is a perspective view of the vibration therapy device with the micro-current cap module exploded therefrom;

FIG. 11 is a rear perspective view of a micro-current cap module;

FIG. 12 is a perspective view of the vibration therapy device with the cleansing cap module exploded therefrom;

FIG. 13 is a perspective view of the vibration therapy device with a treatment member exploded therefrom;

FIG. 14 is a perspective view of the therapy member;

FIG. 15 is a cross-sectional view of the therapy member on the reciprocating attachment;

FIG. 16 is a perspective view of the therapy member in packaging with the lid partially peeled back;

FIG. 17A is a view showing the user interface and display with the light ring module symbol and vibration symbol illuminated;

FIG. 17B is a view showing the user interface and display with the heat ring module symbol and battery symbol illuminated;

FIG. 17C is a view showing the user interface and display with the micro-current cap module symbol illuminated;

FIG. 18 is top perspective view of a cooling attachment module in accordance with a preferred embodiment of the present invention;

FIG. 19 is a bottom view of the cooling attachment module of FIG. 18;

FIG. 20 is an exploded view of the cooling attachment module;

FIG. 21 is a cross-sectional view of the cooling attachment module taken through the cooling protrusions; and

FIG. 22 is a cross-sectional view of the cooling attachment module taken through the spacer members between the cooling protrusions.

Like numerals refer to like parts throughout the several views of the drawings.

DETAILED DESCRIPTION OF THE PREFERRED EMBODIMENTS

The following description and drawings are illustrative and are not to be construed as limiting. Numerous specific details are described to provide a thorough understanding of the disclosure. However, in certain instances, well-known or conventional details are not described in order to avoid obscuring the description. References to one or an embodiment in the present disclosure can be, but not necessarily are references to the same embodiment; and, such references mean at least one of the embodiments. If a component is not shown in a drawing then this provides support for a negative limitation in the claims stating that that component is "not" present. However, the above statement is not limiting and in another embodiment, the missing component can be included in a claimed embodiment.

Reference in this specification to "one embodiment," "an embodiment," "a preferred embodiment" or any other phrase mentioning the word "embodiment" means that a particular feature, structure, or characteristic described in connection with the embodiment is included in at least one embodiment of the disclosure and also means that any particular feature, structure, or characteristic described in connection with one embodiment can be included in any embodiment or can be omitted or excluded from any embodiment. The appearances of the phrase "in one embodiment" in various places in the specification are not necessarily all referring to the same embodiment, nor are separate or alternative embodiments mutually exclusive of other embodiments. Moreover, various features are described which may be exhibited by some embodiments and not by others and may be omitted from any embodiment. Furthermore, any particular feature, structure, or characteristic described herein may be optional. Similarly, various requirements are described which may be requirements for some embodiments but not other embodiments. Where appropriate any of the features discussed herein in relation to one aspect or embodiment of the invention may be applied to another aspect or embodiment of the invention. Similarly, where appropriate any of the features discussed herein in relation to one aspect or embodiment of the invention may be optional with respect to and/or omitted from that aspect or embodiment of the invention or any other aspect or embodiment of the invention discussed or disclosed herein.

The terms used in this specification generally have their ordinary meanings in the art, within the context of the disclosure, and in the specific context where each term is used. Certain terms that are used to describe the disclosure are discussed below, or elsewhere in the specification, to provide additional guidance to the practitioner regarding the description of the disclosure. For convenience, certain terms may be highlighted, for example using italics and/or quotation marks: The use of highlighting has no influence on the scope and meaning of a term; the scope and meaning of a term is the same, in the same context, whether or not it is highlighted.

It will be appreciated that the same thing can be said in more than one way. Consequently, alternative language and synonyms may be used for any one or more of the terms discussed herein. No special significance is to be placed upon whether or not a term is elaborated or discussed herein. Synonyms for certain terms are provided. A recital of one or more synonyms does not exclude the use of other synonyms. The use of examples anywhere in this specification including examples of any terms discussed herein is illustrative only, and is not intended to further limit the scope and meaning of the disclosure or of any exemplified term. Likewise, the disclosure is not limited to various embodiments given in this specification.

Without intent to further limit the scope of the disclosure, examples of instruments, apparatus, methods and their related results according to the embodiments of the present disclosure are given below. Note that titles or subtitles may be used in the examples for convenience of a reader, which in no way should limit the scope of the disclosure. Unless otherwise defined, all technical and scientific terms used herein have the same meaning as commonly understood by one of ordinary skill in the art to which this disclosure pertains. In the case of conflict, the present document, including definitions, will control.

It will be appreciated that terms such as "front," "back," "top," "bottom," "side," "short," "long," "up," "down," "aft," "forward," "inboard," "outboard" and "below" used

herein are merely for ease of description and refer to the orientation of the components as shown in the figures. It should be understood that any orientation of the components described herein is within the scope of the present invention.

Referring now to the drawings, which are for purposes of illustrating the present invention and not for purposes of limiting the same, the drawings show a vibration therapy system 10 that includes a vibration therapy device 12, one or more reciprocating attachments 19 and one or more therapy modules 11. The reciprocating attachments can have different shapes. The therapy modules 11 can have different shapes and include different types of therapy, such as light, micro-current, heat, cold, vibration, etc.

As shown in FIGS. 1-3, generally the vibration therapy device includes a housing 13 (two housing halves 13a and 13b are shown in FIG. 3), a handle portion 14, a head portion 15 and a switch 16 for activating the motor 17. FIGS. 1-8 show the vibration therapy device 12 with a therapy module 11 that is referred to herein as a ring module 18 (due to its shape with a central opening 18a) and a reciprocating attachment 19. As shown in FIG. 3, in a preferred embodiment, the vibration therapy device 12 includes an electrical source, such as a battery 20, positioned in the handle portion 14, the motor 17 positioned in the head portion 15, and a push rod assembly 21 operatively connected to the motor 17 and configured to reciprocate in response to activation of the motor 17.

In a preferred embodiment, the rotation of the motor shaft 22 is converted to reciprocating motion of the push rod assembly 21. As shown in FIGS. 3-5, in a preferred embodiment, the push rod assembly 21 includes a push rod 23 that is pivotably connected to a reciprocating shaft 24 (see pivot pin 25), and an attachment member 26 that is operatively connected to the reciprocating shaft 24. In a preferred embodiment, the shaft 26a of the attachment member extends into and is connected within (via threads, friction fit, interference fit, etc.) an opening 24a defined in the reciprocating shaft 24. The distal end of the attachment member 26 (which is also the distal end of the push rod assembly 21) removably receives the reciprocating attachment 19. It will be appreciated that the term push rod assembly used herein includes any of the drive train components discussed herein or combinations thereof, e.g., push rod 23, reciprocating shaft 24 and attachment member 26 or the like that provide reciprocating motion and include the reciprocating attachment on the distal end thereof. The push rod assembly also includes the attachment member 26 (and any related components, such as the magnet described below) or any other connector at the end of the reciprocating components that allows connection of a reciprocating attachment to be used for massage or therapy.

Preferably, the drive train also includes a counterweight member 28 between the motor shaft 22 and the push rod 23. The motor shaft 22 is received in an opening in the counterweight member 28 and an offset shaft 29 extends from the counterweight member 28 and is received in an opening in the push rod 23. The reciprocating shaft 24 extends through the bush 31 and bush holding structure 33.

In a preferred embodiment, the motor 17 is secured to a motor mount 30 that includes a plurality of feet 32 that are secured to the housing 13 via threaded fasteners or the like that extend through openings in the feet 32. Dampening rings 34 and dampening washers can also be included. All dampening components herein are made of rubber, silicone or the like and are provided to prevent plastic to plastic or plastic to metal contact and to reduce noise and vibration.

In a preferred embodiment, the attachment member 26 includes the shaft 26a and a magnet seat 26b. The magnet seat 26b includes a magnet 27 received therein or otherwise operatively associated therewith. As shown in FIG. 3, the housing 13 includes a cap portion 35 that includes the module seat 50 and a protrusive portion 36. The attachment member 26 extends through an opening in the cap portion such that the magnet seat 26b is located outside of the housing 13, and particularly, the protrusive portion 36 of the housing 13. As described above, The distal end of the attachment member 26 (the magnet seat 26b) removably receives the reciprocating attachment 19. In a preferred embodiment, the magnet 27 in the attachment member is magnetically attracted to a magnet 27 in the reciprocating attachment 19 or other component placed on the attachment member 26. FIG. 3 shows an exemplary reciprocating attachment 19 including the main body portion 19a, inner support portion 19b and magnet 27.

As shown in FIG. 2, in a preferred embodiment, the head portion 15 includes a module seat 50 that removably receives the therapy modules 11. As shown in FIG. 6, the vibration therapy system 10 includes an attachment system 44 for properly aligning or mounting and attaching or securing the various therapy modules 11 on the module seat 50, as well as providing electrical connection or communication (if needed) between the therapy modules 11 and the vibration therapy device 12. In a preferred embodiment, the attachment system 44 includes magnetic attraction between the module seat 50 and therapy module 11 and includes one or more complementary securement protrusions 48 and securement recesses 54 extending or protruding from the module seat 50 and/or the back of the therapy module 11. The securement protrusions are received in the securement recesses. The attachment system 44 provides the ability to accommodate the swappable or interchangeable therapy modules 11 (e.g., ring module 18) with different facial treatment technologies.

As shown in FIGS. 6-7, in a preferred embodiment, one securement protrusion 48 extends from the back of the therapy module 11 and one securement recess 54 is defined in the module seat 50. Also, one securement recess 54 is defined in the back of the therapy module 11 and one securement protrusion extends from the module seat 50. In a preferred embodiment, at least one of the securement protrusions and at least one of the securement recess include one or more magnet members 52 associated therewith that are magnetically attracted to one another, that help secure the ring module 18 (or other therapy module 11) onto the module seat 50 and the vibration therapy device 12. One, two or more magnet members can be included. The magnet members 52 are located within the housing of the therapy module and with the housing of the head portion. One or more magnet members 52 can also be located at other positions around the module seat 50 and the back of the therapy module 11.

In a preferred embodiment, the system includes an electrical connection system 58 between the vibration therapy device 12 and the therapy module 11. In a preferred embodiment, the therapy module 11 includes male electrical contacts 60 extending therefrom (see FIGS. 6 and 10) and the module seat 50 includes complementary female electrical contacts 62. Power is supplied from the battery 20, through the male and female electrical contacts and to the LEDs or other powered components. It will be appreciated that the male and female electrical contacts can be reversed. In a preferred embodiment, the male or female electrical contacts are associated with one of the securement recesses 54 and

one of the securement protrusions 48. In the embodiment shown in the drawings, the securement protrusion 48 that extends from the back of the therapy module 11 is a magnetic securement protrusion and the securement recess 54 that is defined in the module seat 50 is a magnetic securement recess. Furthermore, the securement recess 54 that is defined in the back of the therapy module 11 is an electrical securement recess (and includes male electrical contacts) and the securement protrusion 48 that extends from the module seat 50 is an electrical securement protrusion (and includes female electrical contacts).

As shown in FIG. 1, in a preferred embodiment, the handle portion 14 forms an angle of about 120 degrees with the reciprocating shaft 24 to avoid blocking the user's view during treatment. Anywhere between 90 degrees and 180 degrees is within the scope of the invention. In another embodiment, the head portion can be rotatable and/or pivotable and/or swivelable with respect to the handle portion 14.

FIG. 8 shows the components of the light ring module 18 including the printed circuit board 37 including the LEDs 38 and proximity sensors 39. In a preferred embodiment, the proximity sensors 39 are positioned approximately 180° from another. With respect to 180°, approximately means within 10°. However, they can be positioned anywhere around the ring. The proximity sensors 39 are provided so that LED lights in the light module only turn on (or go from dimmed to "treatment level" or off to "treatment level") when they are less than a predetermined distance from or the lens is in contact with the user's face or skin. In a preferred embodiment, one proximity sensor 39 is located at about twelve o'clock on the PCB and the other is located at about six o'clock. In use, after activating the light ring module, the lights remain off or in a dimmed state until the front surface of the module is placed within a predetermined distance of the user's face, at which point the lights brighten to a treatment level (where the lights will be effective for the desired treatment—e.g., red LED treatment, blue LED treatment or infrared). Preferably, the proximity sensors are programmed such that they only determine the proximity at intervals or at a predetermined frequency (e.g., every one second) so that the lights are not turning on and off every time the device is pulled away from the face or angled during use on the face such that the proximity sensor is out of range. Any type of proximity sensor can be used. In a preferred embodiment, the proximity sensor emits a beam that is reflected by the user's face. The sensor determines the distance with the face based on the time (or frequency) for the beam returning from the user's skin after reflection. It will be appreciated that by having two proximity sensors 180° apart, as long as one is within the predetermined range of distance from the skin (operating surface), the lights will not dim or turn off (or go to a point that is less than the desired treatment level or intensity of the lights).

As shown in FIG. 8, in a preferred embodiment, the light ring module includes a housing portion 40, PCB 37, cover or lens 41 and a light direction member 42 that includes a plurality of openings 43 defined therein. The openings 43 are each aligned with an LED 38 and provide a tunnel so that the light beams emitted from each of the LEDs are directed generally parallel to one another and, therefore, generally perpendicular to the cover 41 and the user's skin as the device is used. This helps prevent the light from shining outwardly and into the user's eyes during use. The ring module includes the central opening 18a and an outer surface 41a. As shown in FIG. 5, in a preferred embodiment, the contact surface 19c of the reciprocating attachment 19

extends further from the module seat 50 than the outer surface 41a of the ring module 18. Other types of ring modules with other therapies are in the scope of the present invention.

FIGS. 9-11 show another type of therapy module 11 referred to generally herein as a cap module and more specifically (for this particular module) as a micro-current cap module 118 that covers the magnet seat 26b of the attachment member 26. The micro-current cap module 118 includes a main body portion 70 and a rear recess 72 defined therein that receives the attachment member 26 when the micro-current cap module 118 is fitted on the module seat 50. The micro-current cap module 118 shown in FIGS. 9-11 includes micro-current therapy. However, different cap modules can include other therapies. Micro-current therapy can also be included in a ring module. The micro-current cap module 118 includes first and second terminals or an anode and cathode 120. This module includes an electrical connection and magnetic attraction just like the ring module 18 described above. As will be appreciated by those of ordinary skill in the art, when the anode and cathode 120 are placed against a user's skin, an electrical connection is created and micro-current is transmitted into the user's skin to provide micro-current treatment.

FIG. 12 shows another type of cap module referred to herein as a cleansing cap module 74 that includes a plurality of bristles 76 thereon. The cleansing cap module 74 includes a main body portion 70 and recess that receives the attachment member 26 when the cleansing cap module 74 is fitted on the module seat 50. The cleansing cap module 74 may also include (but preferably does not include) an electrical connection just like the ring module 18 described above. The cleansing cap module 74 preferably also includes a magnet 27 therein that is magnetically attracted to and connects to the magnet 27 in the attachment member 26. As a result, in use, the cleansing cap module 74 reciprocates against the user's skin. In a preferred embodiment, the main body portion 70 preferably includes the complementary securement protrusions and recesses, like the other therapy modules 11. Therefore, the cleansing cap module is configured to be removable secured to both the attachment member 26 (e.g., via magnets) and to the module seat 50 (e.g., via the complementary securement protrusions and recesses and/or magnet members). However, the complementary securement protrusions and recesses can also be omitted since connection is made between the central magnet 27 and the magnet in the attachment member 26. A cleansing formulation can be placed on the bristles 76 during use.

FIGS. 13-16 show a preferred embodiment system for attaching a component with microfiber material thereon (referred to herein as a skin treatment member 88) to the reciprocating attachment 19. In a preferred embodiment, the skin treatment member 88 includes lotion or some type of skin treatment ointment or fluid thereon and, therefore, is packaged in a pod member 90 that includes a container portion 92 and a lid 94. In a preferred embodiment, the skin treatment member 88 includes a generally ring shaped main body portion 96 and a delivery portion 98 that is preferably made of microfiber and includes the lotion thereon.

In a preferred embodiment, the skin treatment member 88 is attachable or securable to the reciprocating attachment 19. Preferably, the main body portion 96 includes one or more ridge members 100 on the inside surface thereof and extending inwardly that are received in one or more grooves 102 defined in the outer surface of the reciprocating attachment 19. The skin treatment member 88 preferably also includes a handle or tab 106 extending from the main body portion 96

that aids with attachment and removal of the skin treatment member 88 from the reciprocating attachment 19. In use, the skin treatment member 88 is removed from the pod member 90 (by peeling back the lid 94) and the treatment member is placed or seated on the reciprocating attachment 19. It will be appreciated that the main body portion 96 is made of a flexible material (such as plastic) so the ridge members 100 flex over the reciprocating attachment 19 and snap into the groove 102 on the outer surface of the reciprocating attachment. The delivery portion stretches across or spans the top or outer contact surface of the reciprocating attachment 19. The delivery portion 98 is then placed against the user's face and the device is activated such that the reciprocating attachment 19 (also referred to herein as a mallet) with the treatment member 88 thereon vibrates or percusses against the user's skin. After use, the user can pull on the tab 106 to separate the treatment member 88 from the mallet 19. As shown in FIG. 11, the skin treatment member 88 can be placed on the mallet 19 when the ring module 18 is on the device. Therefore, the LED light therapy can be used simultaneously with the vibration therapy and the treatment member therapy. The groove 102 is preferably located further from the module seat 50 than the outer surface 41a or outside of the ring module so that the skin treatment member 88 secured in the groove can reciprocate outside of the ring module.

FIGS. 17A-17C show a control center 108 (or user interface—UI) that includes a display screen 110 and one or more buttons and/or switches that can be used for controlling the device 12 and the various therapy modules 11. The buttons can control different modes, different intensities, etc. In a preferred embodiment, the control center includes display screen 110, motor toggle button 126 (for toggling through different frequencies or speeds for the attachment member 26 and any reciprocating attachment thereon), module toggle button 128 (for toggling through different intensities or options for the therapy modules electrically connected to the device) and a power switch 16. FIG. 17A shows the display screen 110 with the motor speed level 112 at the top and the therapy module level 114 (with the light ring module symbol thereon) at the bottom. FIG. 17B shows the display screen 110 with the battery level 116 at the top and the therapy module level 114 (with the heat ring module symbol thereon) at the bottom. FIG. 17C shows the display screen 110 with nothing on the top and the therapy module level 114 (with the micro-current symbol thereon) at the bottom. Other symbols and the like that can be shown in the display screen include Bluetooth. It will be appreciated that the control center 108 is in data communication with the controller and associated components for controlling the device 12. Preferably, the device can sense or determine what type of therapy module has been seated on an electrically connected to the device. This allows the module toggle button 128 to toggle through the modes of the proper module and for the proper therapy module level to be displayed on display 110. Furthermore, in use, when a cap module (e.g., micro-current module 118) is seated on the module seat and electrically connected to the device, the motor is not activated (to reciprocate the attachment member) because the attachment member and magnet seat is located inside the cap module. When a ring module is seated on the device, the motor can be activated so that the reciprocating attachment can reciprocate within the central opening of the ring module.

It will be appreciated that all or some of the components discussed herein can be contained, sold or distributed in a kit. In other words, the vibration therapy system can be

provided to users as a kit (e.g., within a case, box, bag or the like). The kit can include the vibration therapy device, one or more reciprocating attachments and one or more therapy modules. For example, an exemplary kit includes the device, the light ring module, the micro-current cap module, the reciprocating attachment with the groove therearound and a charger all within a case or container.

FIGS. 18-22 show a preferred embodiment of a cooling attachment module 130 that can be used with the vibration therapy device 10. As shown in FIGS. 18-19, in a preferred embodiment, the cooling attachment module 130 includes first and second cooling protrusions 132, cover member 134 and heat sink member 136. Similar to other attachment modules discussed herein, preferably, the cooling attachment module 130 also includes a securement protrusion 48 that extends from the back or bottom thereof (and mates with the securement recess 54 in the module seat 50), and a securement recess 54 defined in the back thereof that mates with the securement protrusion on the module seat 50.

The cooling attachment module 130 also preferably includes male electrical contacts 60 extending therefrom that mate with complementary female electrical contacts 62 on the module seat. Power is supplied from the battery 20, through the male and female electrical contacts and to the controllable temperature element (described further below) or other powered components. It will be appreciated that the male and female electrical contacts can be reversed. In a preferred embodiment, the male electrical contacts are associated with the securement recesses 54.

As shown in FIGS. 20-21, in a preferred embodiment, the cooling attachment module 130 includes cover member 134 spreader member 138 (with cooling protrusions 132) one or more controllable temperature elements 140, heat sink member 136, pcb member or electrical control member 142 and base portion 144. The cover member 134 includes first and second cooling protrusion openings 146 defined therein through which the cooling protrusions extend 132 so that they can contact the user's body part/skin in use.

From a review of the drawings, it will be appreciated that the heat sink member 136 is also the housing of the cooling attachment module 130. The heat sink member 136 includes a cooling recess 148 (preferably ring shaped) defined in the upper surface thereof and, as shown in FIG. 21, the controllable temperature element 140 is positioned in the cooling recess 148 with spreader member 138 positioned on and in contact with the upper surface of the controllable temperature element 140. The cover member 134 is positioned over the cooling recess 148 and is secured to the heat sink member 136 to contain the controllable temperature element 140 and spreader member 138 within the cooling recess 148. The controllable temperature element 140 is configured to transfer thermal energy to a lower surface of the spreader member 138 and the cooling protrusions 132 extend through the cover member 134 and outside of the cooling recess 148 for contact with the user's body part. PCB 142 is in electrical communication with the controllable temperature element 140. Cooling of the upper surface of the controllable temperature element 140 causes the lower surface to heat up, which heat is dissipated through the heat sink member 136. The heat sink member 136 also includes inner and outer walls 150 and 152 and includes a central opening 166 defined therethrough. It will be appreciated that the term cooling is used herein as the commercial embodiment of the invention is directed to cold therapy. However, it will be appreciated that this is not limiting and the device can also be used for heating. The controllable temperature element can be configured to transfer hot or cold to the spreader

member. Therefore, the use of cooling within the claims or anywhere else herein can also include heating or any transfer of thermal energy.

The lower surface of the controllable temperature element 140 is in contact with heat sink member 136, which is configured to pull or dissipate heat from the lower surface of the controllable temperature element 140. It will be appreciated that a heat sink is able to dissipate more heat based on having a greater surface area. Therefore, the heat sink member 136 or housing is much thicker (in an axial direction) than the controllable temperature element 140, thereby providing inner and outer surfaces (the inner surface of the inner wall 150 and that outer surface of the outer wall 152 that provide a large amount of surface area for heat dissipation). As shown in FIG. 21, the heat sink member 136 is a unitary or single piece that is made of a metal that conducts heat away from the lower surface of the controllable temperature element 140, to the inner and outer walls 150 and 152, where the heat is dissipated to the air.

In a preferred embodiment, the base member 144 includes one or more magnet members 52 associated therewith that help secure the cooling attachment module 130 onto the module seat 50 and the vibration therapy device 12. One, two or more magnet members can be included. The magnet members 52 are received in magnet recesses 154 defined in the base portion 144.

In a preferred embodiment, one or more electrical communication tunnels 155 or paths are defined through the heat sink member 136 (defined between the upper surface and the lower surface of the heat sink member) and power is routed from the electrical connector (the male electrical contacts 60 in the embodiment in the drawings) through the electrical communication tunnel 155 and to the controllable temperature element 140. Preferably, a one or more wires or the like (not shown) are routed through the electrical communication tunnel 155 to power the controllable temperature element 140. Preferably, the heat sink member 136 also includes a component tunnel 157 (which may be used as an electrical communication tunnel) that includes a number of components therein. As shown in FIG. 20, the heat sink member 136 may include a waterproof washer 156 and an isolation washer 158 positioned in each component tunnel 157. In an embodiment, these components may include openings through the center thereof for at least partially defining the electrical communication path to the controllable temperature element 140. The isolation washer 158 can include upwardly extending protrusions that define a recess therebetween. In a preferred embodiment, one or more heat insulation gaskets 160 are positioned between the controllable temperature elements 140. The heat insulation gaskets 160 include an opening defined therethrough. One or more fixed buckles 162 may also be included on an inner or outer surface of the cover member 134 and adjacent the first and second cooling protrusion openings 146.

Unless the context clearly requires otherwise, throughout the description and the claims, the words "comprise," "comprising," and the like are to be construed in an inclusive sense, as opposed to an exclusive or exhaustive sense; that is to say, in the sense of "including, but not limited to." As used herein, the terms "connected," "coupled," or any variant thereof, means any connection or coupling, either direct or indirect, between two or more elements; the coupling of connection between the elements can be physical, logical, or a combination thereof. Additionally, the words "herein," "above," "below," and words of similar import, when used in this application, shall refer to this application as a whole and not to any particular portions of this application. Where

the context permits, words in the above Detailed Description of the Preferred Embodiments using the singular or plural number may also include the plural or singular number respectively. The word "or" in reference to a list of two or more items, covers all of the following interpretations of the word: any of the items in the list, all of the items in the list, and any combination of the items in the list.

The above-detailed description of embodiments of the disclosure is not intended to be exhaustive or to limit the 10 teachings to the precise form disclosed above. While specific embodiments of and examples for the disclosure are described above for illustrative purposes, various equivalent modifications are possible within the scope of the disclosure, as those skilled in the relevant art will recognize. Further, 15 any specific numbers noted herein are only examples: alternative implementations may employ differing values, measurements or ranges.

Although the operations of any method(s) disclosed or described herein either explicitly or implicitly are shown and 20 described in a particular order, the order of the operations of each method may be altered so that certain operations may be performed in an inverse order or so that certain operations may be performed, at least in part, concurrently with other operations. In another embodiment, instructions or sub- 25 operations of distinct operations may be implemented in an intermittent and/or alternating manner.

The teachings of the disclosure provided herein can be applied to other systems, not necessarily the system described above. The elements and acts of the various 30 embodiments described above can be combined to provide further embodiments. Any measurements or dimensions described or used herein are merely exemplary and not a limitation on the present invention. Other measurements or dimensions are within the scope of the invention.

Any patents and applications and other references noted 35 above, including any that may be listed in accompanying filing papers, are incorporated herein by reference in their entirety. Aspects of the disclosure can be modified, if necessary, to employ the systems, functions, and concepts of the 40 various references described above to provide yet further embodiments of the disclosure.

These and other changes can be made to the disclosure in light of the above Detailed Description of the Preferred Embodiments. While the above description describes certain 45 embodiments of the disclosure, and describes the best mode contemplated, no matter how detailed the above appears in text, the teachings can be practiced in many ways. Details of the system may vary considerably in its implementation details, while still being encompassed by the subject matter disclosed herein. As noted above, particular terminology used when describing certain features or aspects of the disclosure should not be taken to imply that the terminology is being redefined herein to be restricted to any specific 50 characteristics, features or aspects of the disclosure with which that terminology is associated. In general, the terms used in the following claims should not be construed to limit the disclosures to the specific embodiments disclosed in the specification unless the above Detailed Description of the Preferred Embodiments section explicitly defines such 55 terms. Accordingly, the actual scope of the disclosure encompasses not only the disclosed embodiments, but also all equivalent ways of practicing or implementing the disclosure under the claims.

While certain aspects of the disclosure are presented 60 below in certain claim forms, the inventors contemplate the various aspects of the disclosure in any number of claim forms. For example, while only one aspect of the disclosure

is recited as a means-plus-function claim under 35 U.S.C. § 112, ¶6, other aspects may likewise be embodied as a means-plus-function claim, or in other forms, such as being embodied in a computer-readable medium. (Any claims intended to be treated under 35 U.S.C. § 112, ¶6 will include the words "means for"). Accordingly, the applicant reserves the right to add additional claims after filing the application to pursue such additional claim forms for other aspects of the disclosure.

Accordingly, although exemplary embodiments of the invention have been shown and described, it is to be understood that all the terms used herein are descriptive rather than limiting, and that many changes, modifications, and substitutions may be made by one having ordinary skill in the art without departing from the spirit and scope of the invention.

What is claimed is:

1. A vibration therapy device, comprising:
a housing, comprising:
a handle portion,
a head portion, and
a module seat defined on the head portion;
an electrical source;
a motor positioned in the housing;
a switch for activating the motor;
a counterweight member coupled to the motor and comprising an offset shaft;
a push rod assembly operatively connected to the motor via the offset shaft and comprising a reciprocating shaft, wherein an angle formed between the reciprocating shaft and the handle portion is larger than 90 degrees and less than 180 degrees, such that a reciprocating movement of the reciprocating shaft is at the angle formed between the reciprocating shaft and the handle portion;
a reciprocating attachment removably secured to a distal end of the push rod assembly and configured to provide a first type of therapy; and
a ring module comprising a proximal end with a central recessed surface extending a partial depth from the proximal end to a closed distal end of the ring module, wherein the ring module is removably secured to the module seat, and wherein the ring module is configured to provide a second type of therapy and is in electrical communication with the electrical source.

2. The vibration therapy device of claim 1, wherein the module seat comprises a first electrical connector, and wherein the ring module comprises a second electrical connector in electrical communication with the first electrical connector.

3. The vibration therapy device of claim 1, wherein the ring module comprises an outer surface, wherein the reciprocating attachment comprises a contact surface, and wherein the contact surface of the reciprocating attachment extends further from the module seat than the outer surface of the ring module.

4. The vibration therapy device of claim 3, further comprises a skin treatment member removably secured to the reciprocating attachment, wherein the skin treatment member comprises a delivery portion that is configured to at least partially cover the contact surface of the reciprocating attachment.

5. The vibration therapy device of claim 3, wherein the ring module comprises a plurality of LED lights configured to operate at a treatment level only when the outer surface of the ring module is less than a predetermined distance from an operating surface.

6. The vibration therapy device of claim 5, wherein the ring module further comprises a first proximity sensor and a second proximity sensor that are positioned approximately 1800 from one another within the ring module and are each configured to activate the plurality of LED lights at the treatment level when the outer surface of the ring module is less than the predetermined distance from the operating surface.

7. The vibration therapy device of claim 1, wherein the ring module is configured to be removed from the module seat while the reciprocating attachment is received on the distal end of the push rod assembly.

8. The vibration therapy device of claim 1, wherein the housing further comprises a protrusive portion defined on the head portion and extends from the module seat, and wherein at least a portion of the push rod assembly extends through the protrusive portion.

9. The vibration therapy device of claim 1, wherein the first type of therapy is vibration therapy, and wherein the second type of therapy is one of LED light therapy, radiofrequency therapy, heat therapy, cold therapy, micro-current therapy, cleansing therapy, electric stimulation therapy, or vibration therapy separate from the first type of therapy.

10. A vibration therapy system, comprising:
a vibration therapy device, comprising:
a housing comprising a handle portion, a head portion, and a module seat defined on the head portion;
an electrical source;
a motor positioned in the housing;
a switch for activating the motor;
a counterweight member coupled to the motor and comprising an offset shaft, and
a push rod assembly operatively connected to the motor via the offset shaft,

wherein the push rod assembly comprises a reciprocating shaft and an attachment member, wherein an angle formed between the reciprocating shaft and the handle portion is larger than 90 degrees and less than 180 degrees, such that a reciprocating movement of the reciprocating shaft is at the angle formed between the reciprocating shaft and the handle portion, and the attachment member defines a distal end of the push rod assembly;

a reciprocating attachment configured to be removably secured to the attachment member and configured to provide a first type of therapy;
a ring module comprising a proximal end with a central recessed surface extending a partial depth from the proximal end to a closed distal end of the ring module, wherein the ring module is configured to be removably secured to the module seat, and wherein the ring module is configured to electrically communicate with the electrical source and to provide a second type of therapy; and

a cap module comprising a main body portion and is configured to be removably secured to the module seat, wherein the cap module is configured to electrically communicate with the electrical source and to provide a third type of therapy.

11. The vibration therapy system of claim 10, further comprising a skin treatment member that is configured to be removably secured to the reciprocating attachment, wherein the skin treatment member comprises a delivery portion that is configured to at least partially cover a contact surface of the reciprocating attachment.

12. The vibration therapy system of claim 10, wherein when the ring module is received on the module seat and is

21

electrically communicated with the electrical source, the motor can be activated to reciprocate the attachment member, and wherein when the cap module is received on the module seat and is electrically communicated with the electrical source, the motor cannot be activated to reciprocate the attachment member.

13. The vibration therapy system of claim **10**, wherein the cap module is configured to be removably secured to the module seat and the attachment member.

14. The vibration therapy system of claim **10**, wherein the first type of therapy is vibration therapy, wherein the second type of therapy is one of LED light therapy, radiofrequency therapy, heat therapy, cold therapy, electric stimulation therapy, or vibration therapy separate from the first type of therapy, and wherein the third type of therapy is one of micro-current therapy or cleansing therapy.

15. A vibration therapy device, comprising:

a housing, comprising:

a handle portion,

a head portion, and

a module seat defined on the head portion;

an electrical source;

a motor positioned in the housing;

a switch for activating the motor;

a counterweight member coupled to the motor and comprising an offset shaft;

a push rod assembly operatively connected to the motor via the offset shaft and comprising a reciprocating shaft, wherein an angle formed between the reciprocating shaft and the handle portion is larger than 90 degrees and less than 180 degrees, such that a reciprocating movement of the reciprocating shaft is at the angle formed between the reciprocating shaft and the handle portion;

a reciprocating attachment removably secured to a distal end of the push rod assembly and configured to provide

5

10

15

25

22

a first type of therapy, wherein the reciprocating attachment comprises a contact surface;

a skin treatment member removably secured to the reciprocating attachment and comprising a delivery portion, wherein the delivery portion is configured to at least partially cover the contact surface of the reciprocating attachment; and

a ring module comprising a proximal end with a central recessed surface extending a partial depth from the proximal end to a closed distal end of the ring module, wherein the ring module is removably secured to the module seat, and wherein the ring module is configured to provide a second type of therapy and in electrical communication with the electrical source.

16. The vibration therapy device of claim **15**, wherein the reciprocating attachment comprises a groove defined therein, wherein at least a portion of the skin treatment member is received in the groove.

17. The vibration therapy device of claim **16**, wherein the skin treatment member further comprises a main body portion, and wherein the main body portion comprises at least one ridge member extending inwardly from the main body portion and received in the groove on the reciprocating attachment.

18. The vibration therapy device of claim **15**, wherein the delivery portion includes a lotion therein.

19. The vibration therapy device of claim **15**, wherein the delivery portion comprises a microfiber material and includes a lotion therein.

20. The vibration therapy device of claim **15**, wherein the first type of therapy is vibration therapy, and wherein the second type of therapy is one of LED light therapy, radiofrequency therapy, heat therapy, cold therapy, electric stimulation therapy, or vibration therapy separate from the first type of therapy.

* * * * *
